HOLDER FOR TUBES, SHAVING GEAR AND THE LIKE

George Wise, Washington, D.C.

Application August 25, 1958, Serial No. 52,365

Term of patent 7 years

(Cl. D4—3)

Fig. 1 is a perspective view of a holder for tubes, shaving gear, and the like, embodying my new design;

Fig. 2 is a front elevational view thereof;

Fig. 3 is a side elevational view thereof; and

Fig. 4 is a top plan view thereof.

The broken away portions represent indeterminate length.

I claim:

The ornamental design for a holder for tubes, shaving gear and the like, substantially as shown and described.
